ELECTRON DISCHARGE DEVICE

Hampton J. Dailey, Bloomfield, N. J., assignor to
Westinghouse Electric Corporation, East Pittsburgh,
Pa., a corporation of Pennsylvania

Application April 8, 1942, Serial No. 438,141

6 Claims. (Cl. 250—27.5)

1

This invention relates to electron discharge devices, and more particularly to appurtenances thereto for prolonging the useful life thereof.

In various electron discharge devices or tubes, especially those employing or developing high power, considerable strain is developed through heat and otherwise which ultimately results in the tube becoming defective or otherwise undesirable or not usable. The prevailing use of anodes and other electrodes as parts of the envelopes, sealed to the glass portions of such envelopes, renders the need for corrective means more imperative. Either a high temperature gradient or a high electro-static field gradient at the seal between the metal and the glass of duplex envelopes such as mentioned, is an adverse gradient and a direct cause of failure of the devices. In tubes utilizing or developing high power, the anode becomes very hot and its situation at the exterior of the tube is desirable for dissipation of heat notwithstanding the resultant complication of temperature gradient between it and the glass. High difference of temperature and high rate of temperature change are both adverse gradients.

The present invention is directed primarily to and has for an object provision of an adequate, practical and readily assembled and applied means for aiding in reduction of detrimental gradients affecting the seal.

A further object is to promote economy of fabrication in effecting attachment of the adverse gradient reducing means to the electrode.

Another object of the invention is to provide a heat exchange or cooling means which will obtain air circulation for the purpose.

A further object of the invention is to provide parts which establish spacing and position of the parts by juxtaposing the same, as well as firmness and non-vibration in use.

Yet another object is to overcome electro-static gradient at the featheredge seal of the metal electrode portion to the glass portion of the envelope.

Still further objects of the invention will appear to those skilled in the art as the description progresses, both by direct statement thereof and by implication from the context.

In the accompanying drawing, wherein like numerals of reference indicate similar parts throughout the several views:

Figure 1 is a sectional elevation of my invention applied to a transmitting tube;

Figure 2 is a horizontal sectional view of the same through the heat exchange means; and

Figure 3 is a perspective view of one of the fine forming parts of the heat exchange means.

2

In the specific embodiment of the invention illustrated in said drawing, the reference numeral 10 designates an electron discharge device in general, the one chosen for exemplification herein being specifically a transmitting tube. Said device or tube, which, of course, utilizes the usual triode electrodes, is shown as having one of those electrodes, namely, metallic anode 11, also constituting a part of the envelope. Said electrode is a generally cylindrical structure with a closed outer end and with its inner end shown featheredged at 12 for obtaining a yieldable junction with the marginal end of portion 13, which is likewise cylindrical but of glass.

Around the cylindrical electrode, such as anode 11 shown, is applied my improved heat-exchange or cooling means 14 which is preferably constituted by a plurality of metallic heat conductive fins 15 radiating from a heat conductive metallic inner collar surrounded by a metallic heat conductive outer collar 19. More specifically, the fins 15 are preferably plates, each having the opposite vertical margins 16, 17 thereof bent laterally in opposite directions forming a Z-shape in cross-section. One of those bent margins is wider than the other, the more narrow one 16 being referred to as the inner flange and the other margin 17 of wider dimension being referred to as the outer flange. The fins are arranged in an annular sequence with the longitudinal edge of the inner margin or flange 16 of one fin bearing against the body surface of the fin next beyond and the longitudinal edge of the outer flange 17 bearing against the body surface of the fin next behind in the sequence. The flange dimensions are made such that the fins will be symmetrically disposed about the inner collar 18 when juxtaposed to each other as just described, and the inner flanges will at such time all be in engagement with said 40 collar which in turn is tightly mounted on the outer surface of the anode 11 and soldered thereto if so desired. It will be observed that the succession of flanges constitutes substantially continuous cylindrical surfaces at the inner and outer ends of the fins. Around the outer cylindrical surface formed by the outer flanges is situated said outer collar 19, both of said collars 18 and 19 being preferably of equal depth as the fins and of appropriate diameter to be in physical contact 50 with the said cylindrical surfaces throughout. The plane of the plate part of each fin, that is, the leg of the Z-shaped cross-section, slopes with respect to a radial plane of the ring intersecting said leg. Variation of that slope may occur in 55 assembly or in use to accommodate the outer

diameter of the fin assembly to the inner diameter of the outer ring.

The flanges 16, 17 of the fins are preferably secured, as by silver solder, to the surfaces against which they abut, whereby the fins are rigidly secured at their inner ends to the inner collar 18 and hence to the electrode and at their outer ends to the outer or fin-encircling collar 19. The structure is therefore firm and will not vibrate, and gives maximum area for heat conduction from the electrode to the fins and from the fins to the outer collar. The mode of fabrication, particularly in attachment of the fins by flanges next the inner collar and similar flanges next the outer collar results in a great saving in machine work and with improved product, especially over constructions where slots have been milled to receive edges of the fins. By virtue of the construction set forth, the body portions of the successive fins are spaced from each other and, with pairs of flanges, provide vertical flues 20 open at top and bottom. A positive circulation of air past the entire fin surface is accomplished and maximum cooling or heat exchange is effected. Heat transmitted by conduction to collar 19 is dissipated from the outer surface thereof by reason of its exposure to the atmosphere. Accordingly the temperature gradient between metallic anode and glass portions of the envelope is reduced materially.

It is likewise desirable to reduce the electric gradient at the juncture of glass and metal. This result is accomplished by providing a metallic sleeve 21 depending from the inside of the anode downwardly past the region of the junction being discussed. This sleeve is within the evacuated envelope.

Outside the envelope, directly opposite the junction of anode and glass parts thereof, is a metallic shielding ring 22 suspended by hangers 23 secured thereto and in turn carried by the heretofore described heat exchange means. As shown, the hangers are in the form of pins the upper ends of which enter certain of the flues 20 of the cooling means next the outer flange of the adjacent fin, said pins being silver soldered in place or otherwise secured.

By use of the inner sleeve or shield 21 and the outer shield or ring 22, the electro-static field at the junction of glass and metal is made zero or very low and thus the glass at the junction is protected from injury which might result otherwise from the electro-static field. The electric gradient and the temperature gradient both being reduced in accordance with my invention the permanence of the seal between the metallic electrode and the glass portions of the envelope has been assured.

Since the various details of construction, as well as the precise relation and functioning of parts are subject to variation and change without departing from the inventive concept or scope of the invention, it is intended that all matter contained in the specification or illustrated in the drawing, shall be interpreted as exemplary and not in a limiting sense.

I claim:

1. In combination, an electron discharge de-

vice having a glass-to-metal substantially cylindrical junction, ring-shaped means carried by said device as part thereof longitudinally displaced from and within effective heat-transfer range of said junction and with the metal and glass margins next the junction fully exposed below said ring-shaped means for reducing adverse temperature gradient affecting said junction, and fins above said exposed margins next the junction extending outwardly from said device to said ring-shaped means supporting the same and transferring heat thereto by conduction.

2. In combination, an electron discharge device having a glass-to-metal substantially cylindrical junction with margins of the metal and glass next said junction exposed outwardly, ring-shaped means encircling said device substantially opposite and within effective electro-static range of said junction for reducing adverse electric gradient affecting said junction, and means carried by an external part of said device at a distance from said junction supporting said ring-shaped means in fixed position opposite said junction.

3. A cooling means for an electron discharge device having a metallic electrode as an outside part of an envelope, comprising a collar around said electrode, a plurality of fins radiating from said collar and having flanges next the collar forming a continuous surface around and in contact with said collar.

4. A cooling means for an electron discharge device having a metallic electrode as an outside part of an envelope, comprising a plurality of fins radiating from said electrode, said fins having flanges at their ends radially outermost, said flanges extending from one fin to the next and successively forming a continuous outer cylindrical surface, and a collar surrounding and in contact with said surface.

5. A cooling means for an electron discharge device having a metallic electrode as an outside part of an envelope, comprising a collar in surface contact with and surrounding said electrode, a plurality of fins radiating from said collar, said fins having flanges at their inner and outer edges, said flanges at the inner edges successively engaging next adjacent fins and forming a continuous cylindrical surface around said collar, said fins having flanges at their ends radially outermost, said flanges extending from one fin to the next and successively forming a continuous outer cylindrical surface, and a collar surrounding and in contact with said outer cylindrical surface.

6. A cooling means for an electron discharge device having a metallic electrode as an outside part of an envelope, comprising a collar surrounding a part of said electrode substantially coaxial therewith and spaced outwardly therefrom, and a plurality of fins extending from said electrode to said collar, said fins sloping away from radial planes intersecting said fins, each fin having flanges at the inner and outer edges thereof with the flange at the inner edge on the opposite side of the fin from the flange at the outer edge whereby said fin is Z-shape in cross section.
